VOLTAGE STEP-DOWN SIGNAL DEVICE

Henry Smith, Central Valley, N.Y., assignor to J. & H. Smith Manufacturing Company, Newburgh, N.Y., a partnership of New York

Filed May 13, 1957, Ser. No. 658,731

7 Claims. (Cl. 307—157)

This invention relates to signal devices and more particularly to combined voltage step-down and indicator light assemblies.

The requirements for indicator light assemblies vary a great deal depending upon the uses to which they are put. The more or less conventional pilot light assemblies, found on test display boards and used in connection with general electronic equipment, are ordinarily of a simple, cheap and flimsy construction. More critical are those indicator lights engineered to perform satisfactorily under the adverse conditions found in military applications as well as certain rugged non-military installations. In these latter areas, a prime requisite for an indicator light is one which is sturdy and shockproof, compact, and moisture resistant, as well as one reasonably inexpensive to manufacture. Hence, the principal object of the present invention is to provide a signal device to satisfy these needs.

A further object of the invention is to provide an indicator light incorporating means for stepping down operating voltages, and arranged so as to contribute to the manufacturing superiority of the over-all signal device.

Heretofore, the usual means employed to obtain lower working voltages from a more or less standard source have included, *inter alia*, transformers. These allow satisfactory voltage reductions whenever rugged service requirements are absent. Economically they may be justified when lower or different operating voltages must be provided for a number of functions, including indicator lights. Even here, however, the problems of wire breakages and their resultant short circuits, weight and size disadvantages, excessive heat losses, etc. tend to mitigate the possible broad advantage obtained by employing such voltage step-down means.

Yet another method of obtaining voltage step-down has been employed; it is the use of capacitors, which means is a substantially cheaper expedient, particularly where the number of signaling devices to be furnished the lower operating voltage is limited. But here too, problems arise. The prevention of surge current, which may burn out signal elements or otherwise interfere with the proper operation of indicator light assemblies, is a problem to which transformers are not subject. For example, if alternating-current power is supplied to an indicator light assembly which is in series with a conventionally fabricated capacitor, the random possibility exists that the connection will be made when the supply voltage is near a maximum excursion. If this happens, the resultant high current surge may burn the lamp filament out. Destruction may be avoided if the lamp is underrated or if it has a high resistance, but both of these preventatives have their own disadvantages. The former is accompanied by a small light output, unless the size of the capacitor is increased, while the latter necessitates a longer and more fragile filament which, in turn, is more susceptible to shock. Some designers, rather than

settle for less illumination or specify larger capacitors, employ separate resistors and/or non-linear devices, e.g., varistors, to prevent the deleterious effects of surge current. These alternatives are not without their own special drawbacks, principal among which are cost, weight and size.

Therefore, another object of the present invention is to provide a signaling device having integral voltage step-down means which are not affected by surge currents.

- 10 A feature of the invention, in accordance with this latter object, pertains to the use of metallized film capacitors of the self-healing type. In these capacitors, a thin layer of aluminum or some other conductive metal is deposited on the dielectric material (e.g. Mylar) to act as an electrode. Two sheets of these electrodes are wound to form the capacitor. This type of capacitor has a number of advantages. Most importantly, temporary short circuits, which occur due to a break or weak spot in the dielectric, are "burned out." This results from 15 the aluminum deposit adjacent the weak spot oxidizing to reestablish the dielectric insulating bond between the capacitor plates. Provided the thickness of the metallic deposit is kept sufficiently small, short circuits will "burn out" and the capacitor will continue to operate as it should without creating a permanent short circuit. These metallized film capacitors also take up less space than their more conventional counterparts.

- 20 The particular structure employed in the instant invention is designed to facilitate the manufacture of an inexpensive and reliable capacitive voltage step-down indicator assembly, and hence, it has a number of novel features designed to further such purpose. One particular feature of the invention is a split body construction to reduce the deleterious effects of vibrations throughout the light assembly as well as to facilitate inexpensive assembly. The cylindrical body is formed of two half-cylinders of a suitable molded resin. The parts are "mirrors," i.e., each is formed in the same die, and contain 25 cavities along their diametral sides, which cavities cooperatively maintain the electrical connectors that link the capacitor electrodes and lamp terminals, in their correct positions. This construction obviates the need for any screws, welding or diverse means to maintain the electrical connectors properly positioned in the interior 30 of the indicator light assembly.

- 35 Another feature of the invention pertains to the use of a cylindrical sleeve threaded on its outer surface and which fits over the upper portion of the body to maintain the body assembly together when the two parts 40 thereof are in contiguous positions along their plane surfaces. Threadedly engaging the outer threaded surface of the sleeve is a conventional lens or jewel holder.

- 45 Another feature pertains to the use of an intermediate 50 external portion of the body assembly as a mandrel for the metallized film capacitor, with provision being made to connect the proper electric connectors to the capacitor electrodes. Thin conductive tapes attached to the electrical connectors are threaded through cooperating 55 aperture of the body and are appropriately interleaved in the capacitor winding to contact the plates of the capacitor. This makes it unnecessary to provide any means for soldering or otherwise terminating the capacitor plates at the terminals.

- 60 Yet another feature of the capacitor relates to the manner in which it is connected. The two connecting tapes are interleaved in the winding so that each capacitor plate is contacted at an opposite end of the winding and at one point only. As a consequence, the current in each capacitor plate must flow in a convolutional path of considerable length as compared to the flow of current in the conventional capacitor. In the latter, con-

nections are often multiplied to the edges of each capacitor plate which requires the charging current to flow only a short distance between the electrodes. As a result, virtually no resistance component is present in most capacitors. Contrariwise, the end-to-end type of connection is used to introduce a considerable resistance, and some inductance into the capacitor circuit. This built-in resistive-inductive effect acts as an effective surge suppressor during transient periods without unduly affecting the steady-state condition.

A further feature of the invention relates to the use of an encapsulating resin, such as an epoxy resin, to retain the body and threaded sleeve in fixed relation and to enclose the capacitor to protect it and related parts of the indicator light assembly. With the encapsulating resin substantially surrounding the body and metallized tape capacitor, a compact, sturdy and moisture resistant voltage step-down indicator light assembly is assured.

These and other objects and features of the invention may be more fully understood when the following description is read with reference to the drawings in which:

Fig. 1 is a perspective of a complete indicator light assembly as it might be affixed to a panel mounting;

Fig. 2 is an exploded perspective of the half-cylindrical piece-parts which form the body assembly as well as the electrical connectors which are positioned within the body;

Fig. 3 is a partial cross-section along a diameter of the complete pilot light assembly of Fig. 1;

Fig. 4 is a perspective of part of the body assembly with the metallized film capacitor partially wound thereon; and

Fig. 5 is the metallized film capacitor unwound to show its construction and orientation with respect to terminal connectors.

Looking more in detail at Fig. 1, it will be seen that the indicator light assembly includes a resin encapsulated body 10 which may fit flush against a mounting panel 12 where it is firmly held by a nut 13 threadedly engaging cooperating sleeve 11. Sleeve 11 is held along its lower shoulder 54 (Fig. 3) by the epoxy resin enclosing the capacitor 59 and light body 20. The lamp filament or bulb 40 extends above upper parts 21 (a, b) of the body 20 (a, b). A threaded cap 14 with a jewel or lens 15 mounted therein is provided to threadedly engage sleeve 11.

Turning to Figs. 2 and 3, which more particularly disclose the relationship between the various parts, it can be seen that the body 20 comprises two identical or mirror parts 20a and 20b. In the exemplary embodiment of the present invention, the body parts 20a, b are molded by employing one of the polyamide resins, e.g. such as commercial nylon. A typical one of these parts, for example, 20b, can be seen to be of a semicylindrical shape with different radii cross sections along its vertical or longitudinal axis. The shoulders 22 (a, b) and 24 (a, b) act as guides or retainers for the metallized tapes 61, 62 (Fig. 4) that form the capacitor 59. The capacitor 59, of course, is wound on intermediate portion 23 (a, b) of the body 20, which portion acts as a mandrel. The uppermost portion 21 (a, b) of the body 20 is the retaining means for the inner portion or aperture of the sleeve 11 (Fig. 3). When the parts of the body 20a and 20b are placed together, the sleeve 11 slides over the outer diameter thereof and abuts the upper surface of the shoulder 22 (a, b).

The flat surface of each semi-cylindrical half of the body 20 has formed in it a number of cavities 25, 27, 28, 29, 30, 31, and 32, all pre-arranged to properly support the electrical connectors 41, 44, and 47 in their respective positions.

The piece-parts which form the electrical path for signal lamp 40 and the capacitor 59 include an L-shaped terminal 41 having a threaded aperture through its lower end 43 which cooperates with a screw 50. On the upper

end of the terminal 41 is fixedly retained a signal light receptacle 42 of cylindrical, open-ended, construction. The surfaces defining the aperture through the receptacle 42 are threaded to cooperate with a signal element 40 having a threaded base. A second, S-shaped, terminal 44 is provided, which terminal has an upper flat portion 45 and a lower end 46 threadedly apertured to cooperate with a screw 50. A thin stainless steel tape 52, which acts as one of the leads to connect the capacitor in series with the filament of lamp 40, is connected to the vertical portion of the S-terminal 44. The strip 52, which is two to three mils thick, is linked through rectangular aperture 55 in terminal 44 and thereafter spotwelded or otherwise affixed to the intermediate portion of terminal 44. And, finally, a connector 47 is provided, it also being S-shaped, which has an upper part 48 and a lower part 49. Welded to the lower end 49 of the connector 47 is a second thin stainless steel tab 53 which acts as the other terminal for capacitor 59.

Considering these electrical connectors and terminals in relation to the cavities illustrated in shell 20b of the body assembly 20, and duplicated in shell 20a, their ultimate positions may be noted. The terminal 41 fits in the left vertical groove 29b with its lower end 43 residing in the cavity 31b and the receptacle 42 fitting into the cavity 25b. The second terminal 44 fits in the right vertical groove 30b with its lower end 46 disposed in cavity 32b, while its upper portion 45 fits into horizontal groove 28b. The intermediate connector 47 lies between terminals 41 and 44 in the upper portion of vertical groove 30b with its upper part 48 resting on surface 26b and its lower end 49 fitting into horizontal cavity 27b. The tab 53 extends downwardly from cavity 27b over the notched portion 33b of the body 20, which notch prevents the tab 53 from extending beyond the outer surface of shoulder 22. This assures a close fit between sleeve 11 and shoulder 22 without endangering strip 53 or capacitor 59. A washer 51 abuts terminal 41 below the receptacle 42 to insulate it from the upper part 48 of the intermediate connector 47. With these parts so positioned, the body piece-parts 20a and 20b are ready to be put together along their flat surfaces. It will be observed (Fig. 3) that the strip 52, attached to the terminal 44, extends outside the split body assembly 20 from between the cooperating flat surfaces and thereafter curves around the mandrel portion 23 of the body 20.

With the electrical connectors 41, 44, and 47 held fixed in their proper cavities by fitting the two parts of the body 20 together, the mandrel 23 is ready to have the metallized film capacitor 59 wound thereon.

Looking to Figs. 4 and 5, which illustrate more clearly the construction of the capacitor 59 itself, it can be seen that the capacitor 59 comprises a pair of dielectric film strips 61 and 62 which have deposited on one of their sides a thin coating of aluminum 63 and 64 which is approximately 40 to 50 millimicrons in thickness. Any suitable condenser paper may be used, but one of the most popular is "Mylar" which is a tough and durable dielectric. Approximately 10 percent of the aluminum coating on each film is oxidized so that when the metallized papers or films are placed one on top of the other, as illustrated in Fig. 5, an overlap of approximately eighty percent is obtained. A typical plate type capacitor is formed when terminals, e.g., such as strips 52 and 53, are connected to respective metallized surfaces 63 and 64. Fig. 5 depicts the construction of the capacitor 59 before it is wound on the mandrel 23. The steel strips 52 and 53 which are ultimately connected to opposite ends of the two capacitive plates, are shown in phantom in these figures to clarify the way in which the connections are made, an important aspect of the invention since it is the key to the built-in resistance of the capacitor. It will be noted (Fig. 5) that the inner metallized strip 61 extends further to the left of the drawing than does strip 62 which underlies it. In the same manner, metallized strip 62

extends further to the right of the drawing than does strip 61. This is to assure that when the film capacitor 59 is wound around the mandrel 23, the terminal strip 52 will engage the metallic surface 63 of tape 61 at one end thereof and that the strip 53 will engage the opposite end of strip 62 on metallic surface 64. The relationship of the capacitor 59 to the mandrel 23 and the lower shoulder 24 of the body 20 is shown in Fig. 4 with the terminal connections 52 and 53 in phantom. Actually, the width of the metallized tapes 61, 62 are less than the width of the mandrel (see Fig. 3) so that no difficulty is experienced in winding the capacitor 59 thereon.

Fig. 3 depicts the assembled pilot light assembly in cross-section with the terminals and connector properly positioned and with the metallized film capacitor 59 connected "end-to-end" to the terminal strips 52 and 53. Fig. 3 additionally illustrates the way in which the encapsulating resin cover 10 engages the lower shoulder 54 on the sleeve 11 to hold it firmly in position on the body 20. The mold (not shown) for forming this cover 10 also permits the resin to "hook" over a portion of the lower surface of shoulder 24 on the body 20.

In the particular embodiment herein disclosed, a capacitor of approximate 0.9 mfd. is obtained by employing 275 turns, more or less. The effective resistance of capacitor 59, end connected, is in the order of 600 ohms. The energization of the indicator light assembly from a conventional 115 volt, 60 c.p.s. alternating current source when the light filament is a low drain one, such as 0.04 amps at 6 volts, assures a pilot light assembly which is substantially impervious to surge phenomena. Voltage variations of plus or minus 10 volts and frequency variation of plus or minus five percent are immaterial. It is apparent, of course, that the effective resistance and capacitance may be varied to cooperate with different power sources.

It will be observed that the component parts and assembly techniques employed in fabricating the present invention have a number of advantages. The use of "mirror" parts for the body assembly cooperating with conductively connecting parts which maintain their correct positions without further operations simplifies manufacture and assembly. Terminating the capacitor without resorting to soldering or other more complex affixing operations compounds the assembly advantages. The over-all effect is a compact, inexpensive and sturdy combination step-down voltage and indicator light device. The device requires no critical parts or tolerances, and further, it requires no skilled operators to assemble it.

It is to be understood, of course, that the above-described arrangements are merely illustrative of the application of the principles of the invention. Numerous other arrangements may be devised by those skilled in the art without departing from the spirit and scope of the invention.

What is claimed is:

1. A combined voltage step-down and signal device comprising a signal element, a two-piece molded body having two shoulders which form a mandrel, said body piece-parts formed with interior cavities, a first terminal having a receptacle for said signal element affixed at one end, conductive strips attached to a second terminal and a connector, said terminals and connector supported properly in said cavities whereby said conductive strips extend outside of said body formed of said piece-parts, a film capacitor having a pair of electrodes and wound on said mandrel so that one electrode at one end of said capacitor contacts the strip affixed to said second terminal and the other electrode at the other end of said capacitor contacts the strip affixed to said connector, said capacitor, terminals and connector completing a series electrical path for said signal element, a sleeve fitting over a part of said body, means for connecting a source of alternating-current power to said terminals, and unitary means enclosing said capacitor and said body and retaining said sleeve on said body.

2. A voltage step-down and indicator light assembly comprising, in combination, a signal element, a two-piece molded body of circular cross section having two shoulders which form a mandrel, said body piece-parts formed with cooperating internal cavities, a first terminal having a receptacle for said signal element affixed to its upper end, conductive strips attached to a second terminal and a connector, said terminals and connector supported in proper relation to each other in said cavities whereby said conductive strips extend outside of said body formed of said piece-parts, a film type capacitor including two contiguous sheets of translucent dielectric upon which have been deposited thin metallic deposits to act as first and second electrodes, said first electrode having a portion extending beyond said second electrode at one end of said film capacitor and said second electrode having a portion extending beyond said first electrode at the other end of said film capacitor, said capacitor wound on said mandrel whereby the extending portion of said first electrode contacts the strip affixed to said second terminal and the extending portion of said second electrode contacts the strip affixed to said connector, said capacitor, terminals and connector completing a series electrical path for said signal element, a tubular member having a shoulder at its lower end and at its outer surface retaining a cap and lens assembly which cooperate with said signal element, said tubular member cooperating with said body whereby the shoulder of said tubular member telescopes over a part of said body and abuts one of the shoulders of said body, means for connecting a source of alternating-current power to said terminals, and a unitary cover of thermosetting resin enclosing said capacitor and said body and retaining said sleeve shoulder adjacent said body shoulder.
3. A combined voltage step-down and signal device for visual display purposes comprising, in combination, a two-piece body of circular cross section having two shoulders which form a mandrel therebetween, said body piece-parts formed with predesigned internal cavities, a signal element mountable within said body, a plurality of terminals for connecting said signal element to a source of alternating-current power, said terminals disposed in the cavities of said body, a film capacitor having first and second electrodes, said capacitor wound on said mandrel so that said first and second electrodes are serially connected in said signal element circuit at the opposite ends of said capacitor, a sleeve supporting a lens assembly for said signal element and fitting over a part of said body to hold said body piece-parts together, and an insulating means enclosing said capacitor and said body and a portion of said sleeve.
4. A signal device comprising, in combination, a split body having a mandrel thereon, a signal element mountable within said body, a plurality of terminals for connecting said signal element to a source of alternating-current power, means integral with said body for supporting said terminals within said body, a convolutional film capacitor having first and second electrodes and wound on said mandrel so that said electrodes are serially connected in said signal element circuit at opposite ends of the capacitor, a sleeve fitting over a part of said body to hold said split body together, and an insulated cover enclosing said capacitor, said body and a portion of said sleeve.
5. A signal device comprising, in combination, a split body having a mandrel integrally formed thereon, terminals and at least one signal element supportable within said body and cooperating with said terminals, a capacitor wound on said mandrel, and means including said terminals for serially connecting end-to-end the electrodes of said capacitor with said signal element.
6. A voltage step-down and signal device comprising, in combination, a two-piece body of circular cross section having two shoulders which form a mandrel therebetween, said body piece-parts formed with internal cav-

ties, a signal element, a plurality of terminals for connecting said signal element to a source of alternating-current power, said terminals supported in some of the cavities of said body, a film type capacitor including contiguous sheets of dielectric upon which have been deposited metallic particles to act as first and second electrodes, said first electrode having a portion extending beyond said second electrode at one end of said film capacitor and said second electrode having a portion extending beyond said first electrode at the other end of said film capacitor, said capacitor wound on said mandrel whereby said first and second electrodes are serially connected in said signal element circuit by their respective extended portions, a sleeve supporting a lens assembly and having a shoulder at one end, said sleeve fitting over a portion of said body whereby the shoulder of said sleeve abuts one of the shoulders of said body and said lens assembly cooperates with said signal element, and a unitary insulated body enclosing said capacitor and said body and retaining said sleeve shoulder adjacent said body shoulder.

7. A voltage step-down and indicator light assembly for visual display purposes comprising, in combination, a signal element having two terminals, a two-piece body of circular cross section, formed of similar, half-cylinder piece-parts and having upper and lower reduced radii sections, said piece-parts having predesigned cavities formed in their cooperating diametral sides, an L-shaped terminal having an open-ended cylindrical receptacle affixed to its upper end and a power connector at its lower end, an S-shaped terminal having a power connector at its lower end and a thin strip of conductive material attached to its intermediate portion, an S-shaped connector having a thin strip of conductive material attached to its lower end, an insulated washer to electrically separate said L-shaped terminal and said connector, said terminals, connector and washer supported in proper relation to

each other in some of said cavities whereby said conductive strips extend outside of said body formed of said piece-parts and yet not beyond the outermost periphery of said body, a film type capacitor including two contiguous sheets of translucent dielectric upon which have been deposited thin deposits of metal to act as first and second electrodes, said first electrode having a portion extending beyond said second electrode at one end of said film capacitor and said second electrode having a portion extending beyond said first electrode at the other end of said film capacitor, said capacitor wound on said lower reduced radius portion of said body whereby the extending portion of said first electrode contacts said conductive strip affixed to said S-shaped terminal and the extending portion of said second electrode contacts said conductive strip affixed to said connector, said capacitor, terminals and connector in situ completing an electrical path for said signal element when one of said terminals of said signal element engages said receptacle and the other of said terminal contacts the upper part of said connector, a cylindrical sleeve having a shoulder at its lower end and threaded on its outer surface to retain a cap and lens assembly, said sleeve fitting over the uppermost reduced radius section of said body such that the shoulder of said sleeve abuts the body shoulder formed between the two reduced radii parts of said body, means cooperating with said connectors of said terminals to connect a source of alternating-current power thereto, and a unitary insulated body of thermosetting resin to enclose said capacitor and said body and to retain said sleeve shoulder adjacent said body shoulder.
